UNITED STATES PATENT OFFICE

FRANK KUSTERLE, OF KENOSHA, WISCONSIN, ASSIGNOR TO SIMMONS COMPANY, OF NEW YORK, N. Y., A CORPORATION OF DELAWARE

CRIB LOCK

Application filed January 13, 1927. Serial No. 160,792.

This invention relates to crib construction of the type having a sliding side adapted to be raised or lowered to facilitate egress or ingress of the child, and in making up the bed, 5 and more particularly to novel means for locking or fastening the sliding side in a raised or closed position, while permitting the same to be readily unfastened to permit lowering thereof, said construction being such as to greatly simplify the manufacture 10 of the device and to reduce the number of parts heretofore employed, obviating means on the corner posts independent of the guide rods for the sliding side, for engagement by the fasteners proper carried by the top rail of 15 said side or the necessity of mounting the guide rods for rocking movement.

More particularly, the invention embodies 20 a construction in which the guide rods are provided with horizontal upper portions or legs for attachment to the corner posts of the head and foot sections of the bed or crib. These horizontal legs constitute in each instance one of the interlocking parts for engagement by the fasteners carried at the ends 25 of the top rail of the sliding side in a manner to be hereinafter more fully described.

In the accompanying drawings, Figure 1 30 is a sectional inside elevation of one end of the crib and showing the application of the device to a tubular metal crib.

Fig. 2 is an enlarged sectional view taken on the line 2—2 of Figure 1.

Fig. 3 is an enlarged fragmentary perspective view of the device.

Fig. 4 is a view similar to Figure 1 but showing a modified form of the device applied to a crib of wood or one having a frame 40 of rectangular cross-section.

Fig. 5 is an enlarged sectional view taken on the line 5—5 of Figure 4, and

Fig. 6 is an enlarged fragmentary perspective view of the device shown in Figure 4.

Referring to the drawings and particularly to Figures 1, 2, and 3 in which a crib of tubular metal frame construction is shown, 7 designates an end frame which may be either the head or foot having the usual corner posts 50 connected in the usual or any preferred man-

ner and supported on casters if desired. One side of the crib is usually fixed or stationary and the other side 9 is mounted to slide up and down to raised or closed and lowered or open positions. For this purpose there is mounted on the corner post at one side and in position to extend inwardly in the plane between said corner posts—that is, longitudinally of the crib—vertical guide rods 10 which have their lower ends engaged in apertured supports or the like 11, or otherwise suitably secured to brackets 12 or directly attached to the corner posts by parts formed integral therewith. The upper ends of the rods 10 have angular attaching portions 13 including horizontal outwardly extending legs 14 disposed longitudinally of the crib. These horizontal legs are disposed in line with each other at opposite ends of the crib and constitute means for engagement by fasteners on the sliding side, as will hereinafter be more particularly pointed out, without the necessity of providing pivoted hooks or other independent parts which increase the cost of production and are a constant annoyance in use, owing to the fact that such devices readily get out of working order and are difficult to fasten.

The sliding side 9 has upper and lower rails 15 and 16 connected in the usual way and the ends of the upper rail 15 have fasteners 17 thereon. The ends of the lower rail 16 are apertured as at 18 for sliding engagement with the rods 10. Each fastener 17 includes a plate 19 spot-welded or otherwise secured to an end of the rail 15 preferably at the outside and provided at the bottom with a horizontal portion 20 formed as a lateral extension on a stamping or blank from which the part 17 is produced. The portion 20 is bent inwardly horizontally at right angles to the plate and has a slot 21 extending transversely with respect to the crib rail sufficiently to allow movement on the rod 10 about twice as great as the diameter of the rod and preferably slightly greater. The top of the plate 19 is provided with an inwardly and downwardly turned rigid or resilient tongue or extension 22 which substantially bisects the 100

rail but terminates short of the bottom to provide an opening 22^a. The slot 21 is sufficient in length to permit the hook formed by the tongue 22 to engage outwardly of the 5 rod 10 when the sliding side 9 may be readily moved up and down, as shown in full and dotted line positions in Figures 1 and 2. When it is desired to lock or fasten the sliding side in a raised or closed position, the 10 tongue 22 is raised clear of the leg 14 and then the sliding side is displaced inwardly with the portion 14 passing through the opening 22^a, so that the tongue 22 will engage inwardly of or over said leg when the sliding 15 side is dropped, to support the side without the employment of independent hooks or other parts independently of the guide rods. In the form of the invention shown in Figures 4, 5, and 6, the application of the device 20 to a crib frame of wood or rectangular cross-section is shown. Corresponding parts are designated by similar reference characters primed, except that the bracket 13' may be in the form of a plate fitted on the leg 14' 25 instead of formed with or on the end thereof as in Figures 1 and 3, and the leg 14' extends into the corner-post 8' to anchor the rod, in addition to the fastening through the bracket or plate. In this form, instead of having the 30 plate 19 enveloping the end of the top rail of the sliding side of the crib or partially enveloping the same at the top, outer side, and bottom, it may be in the form of a plate 19' secured to the bottom of the rail, as indicated at 23, so that the slotted extension 20' and the curved portion 19' and tongue 22' 35 project from the end of the rail to co-operate with the leg 14' of the guide rod 10' in the same manner as heretofore described. 40 While the brackets or fittings on the ends of the top rail of a metallic tubular frame or sliding side may be fastened externally as shown in Figures 1 to 3 inclusive, it is to be understood that the bracket may be constructed as shown in Figure 6 and the part 45 19' fastened within the tubular frame or top rail of the sliding side by screws or other suitable fasteners and that the downturned part 22 may or may not have an extension anchored to a cap fitted over the end of the top rail to close the same. Also, a nut or 50 separate anchoring plate may be provided in the corner post for securing the screws or other fastenings of the attaching portions 13. 55 The part 19' may be suitably shaped and in connection with wooden cribs, the upper ends of the rods 10' may be fastened in the same manner as the rods 10. In the case of a metal crib frame or sliding side having a solid 60 rod for the top rail, the bracket or fitting may be sleeved or otherwise fastened around the ends of the rod and brazed or welded thereto. 65 While I have shown and described my invention in a preferred form, I am aware that

various changes and modifications may be made therein without departing from the principles of the invention, the scope of which may be determined by reference to the appended claims.

70

I claim as my invention:

1. The combination with crib posts, of guide rods on said crib posts having top portions, a crib side slidable on the rods, and means on the top rail of the sliding side to 75 detachably engage over the top portions of the guide rods, said means including a slotted plate mounting the side to swing laterally on the rods and having a downturned portion adapted in one position to fit over the top portion of the guide rod to support the side in a raised position or to be disengaged therefrom to permit sliding of the side.

2. In a crib lock, the combination with a crib having a corner post and a sliding side, 80 a guide rod on the corner post having a horizontal leg, a bracket on the top rail of the sliding crib side and having a slot receiving the rod to permit lateral shifting of the side, and a downturned tongue spaced from the 85 slot and disposed over the same, said tongue being adapted to engage over the leg when raised above the same and the sliding side is shifted inwardly, to support the side in an elevated position.

3. In a crib construction, end members having posts, guide rods mounted on said posts at the inside and extending longitudinally inward, the upper ends of the rods having horizontal legs and being anchored to the 90 posts, a sliding side mounted to slide on the rods, fittings on the ends of the top rail of the sliding side and having plate portions at the bottom with transverse slots and also having the outer side formed with a curved depending hook adapted to fit against the rods at the outside or to be shifted inwardly through the medium of the slots for engagement over the horizontal legs of the rods when the sliding side is lowered from an 95 elevated position and vice versa.

4. In combination with a crib post, a guide rod on the post extending inwardly longitudinally of the crib and having a top portion, a sliding crib side having a top rail, a bracket on the top rail having a slotted bottom portion receiving the rod to permit lateral shifting of the side, and a downturned tongue spaced from the slot and disposed to extend partially over the same for engaging 100 the top portion of the rod to support the side in a raised position or to disengage therefrom to permit lowering of the side.

5. The combination with crib posts, of guide rods on said crib posts, horizontal members at the top portions of the guide rods, a crib side slidable on the rods, and hooks rigidly mounted at the ends of the top portion of the crib side and extending upwardly therefrom with depending bills, said hooks 105

having slotted portions receiving the guide rods to permit lateral movement of the crib side and hooks when the crib side is raised with the bills of the hooks above the horizontal members to permit the hooks to engage the horizontal members and support the crib side in a raised position, or to permit lowering of the crib side on the guide rods by means of the slotted portions with the hooks 5 disengaged from the horizontal members and moving along the guide rods.

10 6. In combination with a crib having a corner post and a slidable side, a vertical guide rod fixedly secured to said corner post, a horizontal member extending adjacent the upper end of said guide rod between said rod and said post and serving as an upper stop for said crib side, a horizontal plate mounted on said crib side having a slot elongated in a 15 plane transverse to that of said crib side, and a hook integral with said plate and overhanging said slot, said slot receiving said guide rod on which said crib side is slidable and said hook bearing resiliently against said 20 rod when said crib side is being slid thereon in order to prevent rattling of said side and co-operating with said horizontal member to support said side in elevated position.

FRANK KUSTERLE.
